UNITED STATES PATENT OFFICE.

EDWARD GERALD GALLAGHER, OF BRIDGEPORT, CONNECTICUT, ASSIGNOR TO THE LAKE TORPEDO BOAT COMPANY OF MAINE, OF BRIDGEPORT, CONNECTICUT, A CORPORATION OF MAINE.

TORPEDO-FIRING CONTROL AND SIGNAL APPARATUS FOR TORPEDO-BOATS.

1,222,198.

Specification of Letters Patent. Patented Apr. 10, 1917.

Application filed September 14, 1915. Serial No. 50,634.

To all whom it may concern:

Be it known that I, EDWARD GERALD GALLAGHER, a citizen of the United States, residing at Bridgeport, in the county of Fairfield and State of Connecticut, have invented certain new and useful Improvements in Torpedo-Firing Control and Signal Apparatus for Torpedo-Boats, of which the following is a specification.

- 10 This invention relates to an improvement in torpedo firing control apparatus, and has for its object to provide an apparatus operating in conjunction with the mechanism for opening the outboard covers of the tubes, and by which the admission of the firing air to the tube is positively prevented until the outboard cover of the tube has been opened far enough to give free exit to the torpedo when fired from the tube, and in the employment of a signal for indicating the open position of the said outboard cover, the arrangement being such that the firing of a torpedo may be controlled from any station within or upon a boat.
- 25 The invention comprises, in combination with a source of electrical energy, a switch or contact which is normally held open and closed only when the outboard cover of the torpedo tube is in its extreme wide open position, or in such position as to give clearance to the torpedo when fired from the tube; an electric lamp in the circuit which is lighted only when the circuit is completed (when the door is wide open); a solenoid operated valve controlling the admission of firing air to the firing valve, a switch or contact for closing the circuit which energizes the solenoid windings, and a central control switch for connecting and disconnecting the firing and control system from the source of electrical energy, the said central control switch providing a "gap" in the circuit, making it possible to operate the firing valve only when the gap is closed and when the other switches and contacts in the circuit are closed. The energy for supplying the circuit windings of the solenoid operated valve is obtained by such a disposition of the leads or connections that the solenoid windings are placed in parallel relation with the signal lamp, or in other words, across the terminals of the lamp, so that the solenoid windings receive their energy from the same source of energy as the signal lamp, the cir-

cuit of the signal lamp being so arranged that it becomes complete and receives energy only when the switch or contact operated by the opening of the outboard cover of the tube is closed.

The invention further consists in novel details of construction and peculiar combinations and arrangements of parts as will be hereinafter fully described and then claimed.

In the drawings, illustrating the invention, in the several figures of which like parts are similarly designated, Figure 1 is a diagrammatic view illustrating the application of my invention. Fig. 2 is a sectional elevation of a solenoid operated valve, and the mechanism controlling the operation of the firing valve. Fig. 3 is a sectional elevation of the inner end of the shaft for operating the outboard cover of the torpedo tube illustrating the manner of completing the circuit of the signal or lamp when the outboard cover of the tube is wide open. Fig. 4 is a front elevation of the casing containing the lamps or signals and the firing levers, the door on the port sides of the casing controlling access to the lever for the port being removed. Fig. 5 is a horizontal section of the same drawn on the line *a—a* of Fig. 4. Fig. 6 is a vertical section of the same drawn on the line *b—b* of Fig. 4. Fig. 7 is a diagrammatic view showing the location of the switch box relative to the periscope of a submarine. Fig. 8 is a side elevation of the same.

1, Fig. 1, designates a torpedo tube having an inboard cover 9 and an outboard cover 3, the latter being connected to a shaft 4 through a link 5, and upon the shaft 4 is keyed a segmental worm wheel 6, which is meshed by a worm 7 carried at the outer end of a shaft 8, the inner end of said shaft being extended beyond the inboard end of the tube 1, and provided with a hand wheel 9, these parts being of the usual construction. The inner end of the shaft 8 is threaded as at 10 (Figs. 1 and 3), and operating upon the said threaded section is a nut 11 having an arm 12 adapted for engagement with a plunger 13 operating in a casing 14. The inner end of the plunger is formed with a head 15 designed for engagement with contacts 16 held within the casing 14, and which contacts 16 are connected the posi-

and negative wires 17 and 18, respectively, extending from a suitable source of energy 19, shown in Fig. 1 as a battery. A switch 20 is interposed in the circuit wires 17 and 18, whereby the current through the circuit, between the contacts 16 and the battery 19, is controlled; and arranged in this circuit is a signal lamp 21 which is located in a switch casing, as will be hereinafter described. The head 15 is normally held out of engagement with the contacts 16 by means of a spring 22, as shown in Fig. 3. The nut 11 carrying the arm 12 is preferably formed in halves and bolted together so that the threads of the nut will be held in engagement with the threads 10 of the shaft 8 to be thus moved along the shaft 8 when the latter is rotated, whereby to bring the arm 12 into engagement with the plunger 13; and, in order to prevent rotation of the nut 11, I provide the same with a stud bolt or pin 23, which operates in a slot 24 of a bar or arm 24' held at one end to a bracket 25 suitably mounted adjacent to the inner end of the torpedo tube 1, and having its opposite end connected to a sleeve 26 mounted upon the shaft 8. By this arrangement, when the shaft 8 is rotated to open the outboard cover 3 of the torpedo tube 1, through the worm and worm segment, it will be appreciated that the nut 11 will be fed forwardly along the shaft 8 so that the arm 12 will be brought into engagement with the plunger 13, to thus force the head of the plunger into engagement with the contacts 16, so that when the switch 20 is closed, a circuit will be formed and the lamp 21 lighted, thus indicating to the operator that the outboard cover 3 of the torpedo tube has been widely opened, hence avoiding any danger, under ordinary conditions, of admitting the firing air to the torpedo tube until the said outboard cover 3 has been fully opened.

In order to avoid any possibility of the controlling air being admitted to the torpedo tube prior to the opening of the outboard cover thereof, I employ the following arrangement and which is located in the lamp circuit as I will now explain.

27 designates a firing valve casing having a balance valve 28 operating therein and controlling the admission of air to the torpedo tube, the valve being normally held to its seat 29 by a spring 30, and by air pressure as will hereinafter be explained. In the casing is also a back pressure valve 31, normally held to its seat 32 by a spring 33, the said valve 31 serving to prevent water reaching the valve 28 or entering the air line from the air tanks (not shown) after a torpedo has been fired, and water from the surrounding body of water rushes into the tubes. Air under comparatively low pressure is admitted to the casing above the valve 28 through a pipe 34 extending from a suitable source

(not shown) of low pressure air supply, and the air from the said casing below the valve 28 is conducted to the inboard or breech end of the torpedo tube through a pipe 35. The valve casing 27, between the valves 28 and 31, is provided with a vent 36 which serves to permit the escape of the compressed air in the event of leakage past the valve 28. The balance valve 28 is formed with a piston 37 having a vent 38 formed therein to permit the compressed air to enter the valve casing above the piston 37, which, with the spring 30, serves to hold the valve tightly to its seat, it being observed that the piston is of greater area than the valve proper. The upper end of the valve casing 27 is formed with an outlet or vent 39 to which is connected a pipe 40 having its opposite end connected to a cylinder 41, having a vent 42 leading from its upper end. Operating in the cylinder 41 is a piston 43, which in its normal position, serves to close the vent and thus prevent the escape of the low pressure air from the upper end of the casing 27. The rod 43' of the piston extends through the upper end of the cylinder 41 and through the upper end of a cylinder 44, and has its lower end fixed to a piston 45 operating in a cylinder 45', the cylinder 45' is provided with an inlet port 46 which is connected by a pipe 47 with a valve casing 48 to which is connected a pipe 49 extending from a source (not shown) of high pressure air supply. The valve 50 of the casing is, as usual, arranged to be held to its seat by the pressure of the air from the high pressure source of supply, and this valve is lifted from its seat by a solenoid 51, the plunger or core 52 of which is connected to the valve in any suitable manner, and as I make no claim *per se* to the valve 50 or its casing, or to the operation of the valve, it is not thought necessary to dwell in detail upon this construction. The solenoid 51 has its windings (not shown) connected by circuit wires 53 and 53', one of which 53' is connected to the negative circuit wire 17 upon one side of the lamp 21, while the other wire 53 extends to one terminal of a control switch 54 located at any convenient place in or upon the boat, and preferably in the lamp casing to be hereinafter described, and extending from the circuit wire 17 from the opposite side of the lamp 21 is a conducting wire 55, which is connected to the opposite terminal of the switch 54. By this arrangement, it will be observed that when the switch 20 is closed and the outer cover 3 of the torpedo tube has been opened, a circuit will be established from the battery, and the lamp 21 will be lighted, and then when the switch 54 is "thrown," the solenoid will be energized and the valve 50 thus lifted from its seat, which will permit the high pressure air to instantly rush into the upper end of the cylinder 45. 130

above the piston 45, to force the latter downwardly, which correspondingly moves the piston 43 in its cylinder to uncover the port or vent 42 and thus vent the upper end of the valve casing 27 above the piston 37, and the moment the upper end of the valve casing 27 is vented and the air pressure against the upper end of the piston 37 is relieved, the pressure upon the lower side of the piston being greater than that upon the top of the valve proper, the valve will be lifted from its seat so that the firing air may rush through the casing past the valve 31 into the breech end of the tube, thus firing the torpedo.

The control switch 54 is preferably arranged within a casing 56, Figs. 4 and 6, in which casing is also arranged the signal lamp 21. While it is understood that my system is applicable to any number of forward and after torpedo tubes, I have illustrated the same in Fig. 1 as connected with only one tube, whereas in Figs. 4, 5, 6, 7 and 8, I have shown the casing adapted for use with two forward and two after tubes, and as the connections to the several switches and signal lamps are identical, I shall place the corresponding numerals upon the several parts throughout the said Figs. 4, 5, 6, 7 and 8.

The casing 56 is preferably rectangular in shape, and is formed with openings 57, provided with doors 58 controlling access to the levers 59 of the switches 54, the purpose of the doors 58 being to prevent indiscriminate access and possible accidental operation of the switches by a member of the crew other than the one in charge of the control station.

In practice the bulb of each lamp 21 will be inclosed in a metal sleeve 60 carried by a plate 61. In the outer end of each sleeve 60 is arranged a glass closure 62, which, in practice, will be colored red and green to correspond respectively with the port and starboard lights of a boat. The plates 61 are held in recesses 63 formed respectively in the front and rear side of the casing and in which are arranged glass plates 64, which are held in position by frames 65 having gaskets 66 of rubber or other suitable material interposed between them and the casing, and the glass covering 64, whereby to seal the recesses air- and water-tight. The tubes 60 serve the purpose of preventing deflection of the light from one side of the casing to the other, and thus concentrate the light upon the colored glass 62 corresponding to the tube of which the outer cover 3 has been opened, as will be best understood from the general description of the apparatus.

When the system is installed upon a submarine boat, I purpose arranging the casing 56 immediately adjacent to the periscope or sighting tube 75 at the firing control station, as illustrated in Figs. 7 and 8,

and when installed upon a submarine boat having torpedo firing tubes both in the bow and the stern, I construct the casing so that access to the lever or levers controlling the firing of the after tubes may be had from the back of the casing, and also arrange the signal lamps of the after tubes so that they may be visible only from the back of the casing, as illustrated in Figs. 4 and 5, so that when the sighting tube is rotated to view an object in the stern of the boat, ready access to the firing levers of the after tubes may be had by the firing officer or attendant, thus enabling him to throw the switch or switches the instant the command is given.

It will be observed that the arrangement is such that the signal lamp is in parallel relation with the windings of the solenoid, and in series with the contacts 15 and 16, and that one terminal (53') of the solenoid windings is in the circuit between the switch 20 and the signal lamp 21, so that it will be impossible to energize the solenoid windings until after the circuit is complete between the signal lamp and the source of electrical energy. In other words, the circuit of the signal lamp 21 is in parallel relation with the circuit between the source of electrical energy and the contacts 15 and 16 at a point on the line between the switch 14 and the control switch 54, and that the other terminal between the aforesaid elements is in circuit across the return circuit, so that only, when the lamp is energized (and of course, only when the switch 20 is closed), will it be possible to light the signal lamp 21, and render it possible to complete the circuit between the source of electrical energy and the solenoid windings when the switch (54) at the control station is closed.

It will thus be seen that I not only provide an apparatus whereby the open position of the outboard cover of the torpedo tube may be indicated to one in charge of the firing switch, but that I also provide a construction whereby the firing air to the torpedo tube may be admitted only when the outboard cover is "wide open."

The operation of the invention is as follows:

When it is desired to adjust a tube ready for firing a torpedo therefrom, the switch 20 is first closed and the hand wheel 9 of the shaft 8, is then rotated to open the outboard cover 3 of the tube. As the shaft 8 is rotated, the nut 11 will be moved along the shaft, and the arm 12 carried by the nut 11 will be caused to engage the plunger 13 to force the head of the plunger to engage the contact 16 to thus create an electric circuit through the wires 17 and 18, causing the lamp 21 to be lighted, it being understood that a circuit is created only when the switch 20 and the contacts 16 are closed. The tube

is then ready for "firing," and in order to fire the torpedo, the switch 54 at the control station is then closed, thus completing the circuit between the windings of the solenoid 5 and the circuit in which the lamp is arranged, and between the source of electrical energy. The moment a circuit is made through the solenoid windings, the valve 50 will be raised from its seat, to allow the 10 high pressure air to enter the upper end of the cylinder 45', to thus release the piston 45, and thus draw or force the piston 43 downwardly in its cylinder to uncover the vent 42, so that the low pressure air in the 15 upper end of the valve casing 27 may escape and hence release the pressure upon the top of the balance valve. The moment pressure upon the top of the balance valve is released, the pressure upon the lower side of the piston 20 37 will then move the balance valve from its seat, thus allowing the firing air to automatically unseat and to escape the said valve past the check valve 31, and pass out through the connection 35 into the breech end of the 25 torpedo tube.

I make no claim *per se* in this application to the casing nor to the special construction of the switches, and desire it understood that I reserve the right to claim such details in a 30 separate application.

What I claim is:—

1. Torpedo firing control apparatus, comprising in combination with means for operating the outboard cover of a torpedo tube 35 and means to supply firing air to said tube, a source of electrical energy, a solenoid operated valve controlling the admission of firing air to the torpedo tube, the windings of the solenoid being in the circuit of the 40 source of electrical energy, a control switch arranged in the circuit, a signal lamp also arranged in the circuit in parallel relation with the windings of the solenoid, and normally open contacts in the circuit adapted to be closed through and by the means for operating the outboard cover of the tube, for the purposes specified.
2. Torpedo firing control apparatus, comprising in combination with means for operating the outboard cover of a torpedo tube 50 and means to supply firing air to said tube, a source of electrical energy, a solenoid operated valve controlling the admission of firing air to the torpedo tube, the windings of the solenoid being in the circuit of the source of electrical energy, a control switch arranged in the circuit, a signal lamp also arranged in the circuit, and normally open contacts in the circuit adapted to be closed through and by the means for operating the outboard cover of the tube, whereby to energize the signal lamp and render it possible to energize the windings of the solenoid, for the purposes specified.
3. Torpedo firing control apparatus, comprising in combination with means for operating the outboard cover of a torpedo tube 55 and means to supply firing air to said tube, a source of electrical energy, a solenoid operated valve controlling the admission of firing air to the torpedo tube, the windings of the solenoid being in the circuit of the source of electrical energy, a control switch arranged in the circuit, a signal lamp also arranged in the circuit, and normally open contacts in the circuit adapted to be closed through and by the means for operating the outboard cover of the tube, whereby to energize the signal lamp and render it possible to energize the windings of the solenoid, for the purposes specified.

prising in combination with means for operating the outboard cover of a torpedo tube and means to supply firing air to said tube, a source of electrical energy in circuit with the windings of the solenoid, a signal lamp arranged in said circuit, a control switch also arranged in the circuit, and normally open contacts in said circuit adapted to be closed through and by the means for operating the outboard cover of the tube, as specified, the circuit of the solenoid windings being in parallel relation with the signal lamp and across the terminals of the lamp whereby the windings receive energy from the same source of energy as the signal lamp.

4. Torpedo firing control apparatus, comprising in combination with means for operating the outboard cover of a torpedo tube 85 and means to conduct firing air to the tube, a source of electrical energy, a solenoid operated valve controlling the admission of firing air to said torpedo tube, the windings of the solenoid being arranged in the circuit 90 of the source of electrical energy, normally open contacts also arranged in the circuit and adapted to be closed only when the outboard cover of the torpedo tube is open, a lamp arranged in the circuit and adapted to be energized only when said contacts are closed, and a control switch also arranged in said circuit, the arrangement being such that the windings of the solenoid may be energized only when the signal lamp is energized 95 and the control switch is closed.

5. A signal device for torpedo firing tubes, comprising in combination with manually operated means for operating the outboard cover of a torpedo tube, a source of 105 electrical energy, normally open contacts arranged in the circuit of the source of electrical energy adapted to be closed by said outboard cover operating means only when said outboard cover is in its extreme open position, a control switch arranged in circuit with the source of electrical energy, and a signal lamp also arranged to be energized only when said outboard cover of the torpedo tube is in its extreme open position 110 and when said contacts are closed, substantially as specified.

6. Torpedo firing control apparatus for torpedo firing tubes, comprising in combination with means for operating the outboard cover of a torpedo tube, a source of 120 electrical energy, normally open contacts arranged in the circuit and adapted to be closed by and through the outboard cover operating means, as specified, a signal lamp arranged in the circuit adapted to be energized only when the outboard cover is in its extreme open position, and a manually operated switch controlling the firing of the torpedo.

7. Torpedo firing control apparatus, comprising in combination with means for operating the outboard cover of a torpedo tube, and valve controlled means to supply firing air to the tube, a source of electrical energy, a solenoid in the circuit of the source of electrical energy for operating the valve controlling the admission of firing air to the tube, a signal lamp arranged in the circuit 10 of the source of electrical energy adapted to be energized only when the outboard cover of the torpedo tube is in its extreme open position, and a control switch also arranged in the circuit, the arrangement being 15 such as to prevent completion of the circuit to admit firing air to the tube until after the signal lamp is energized.

8. Torpedo firing control apparatus, comprising in combination with means for operating the outboard cover of a torpedo tube and means to supply air under pressure to said tube, a source of electrical energy, a solenoid operated valve controlling the admission of firing air to the torpedo tube, the 25 windings of the solenoid being in circuit with the source of electrical energy, a con-

trol switch arranged in the circuit, a signal lamp arranged in the circuit in parallel relation with the windings of the solenoid, and normally open contacts in the circuit, 30 a head adapted for engagement with said contacts, and an arm carried by and operable through the outboard cover operating means adapted for forcing the head into engagement with said contacts to complete 35 the circuit between the source of electrical energy and the signal lamp, the arrangement being such that the head will be forced into engagement with the contacts only when the outboard cover of the tube is in 40 its extreme open position, and rendering it possible to energize the windings of the solenoid only when the lamp circuit is energized and when the control switch is closed.

In testimony whereof I have hereunto 45 set my hand this 25th day of August, A. D. 1915.

EDWARD GERALD GALLAGHER.
